GAS DRIER

Peter Eduard Geldhof, St. Joseph, Mich., assignor
to Nineteen Hundred Corporation, St. Joseph,
Mich., a corporation of New York

Application March 30, 1946, Serial No. 658,511

8 Claims. (Cl. 263—34)

1

This invention relates to a gas drier and more particularly to a small, compact, unitary clothes and article drier of the type which is suitable for ordinary household use in conjunction with any laundry machine or washing apparatus and which derives its heat from a gas burner within the device.

One type of clothes drier for household use includes a rotating drum through which heated air is circulated. It is one of the principal features and objects of the present invention to provide a novel clothes drier of this general category which gives greatly improved results with a minimum expenditure of energy.

It is a further object of the present invention to provide novel means for heating and circulating air in a clothes or article drier.

It is a still further object of the present invention to provide a horizontally rotating drum type drier having novel structural features and air heating means.

Another and further object of the present invention is to provide novel air circulating and heating means for a clothes drier.

The novel features which I believe to be characteristic of my invention are set forth with particularity in the appended claims. My invention itself, however, both as to its organization, manner of construction and method of operation, together with further objects and advantages thereof, may be best understood by reference to the following description taken in connection with the accompanying drawings in which:

Figure 1 is a rear elevational view of a clothes drier embodying the novel principles and teachings of the present invention with the rear panel of the device removed, as indicated by the line I—I of Figure 2;

Figure 2 is a vertical view of the device partly in section as taken along the line II—II of Figure 1;

Figure 3 is an enlarged fragmentary sectional view as taken along the line III—III of Figure 2;

Figure 4 is an enlarged fragmentary sectional view as taken along the line IV—IV of Figure 2;

Figure 5 is an enlarged fragmentary sectional view as taken along the line V—V of Figure 2;

Figure 6 is a front view showing the general arrangement of the drier; and

Figure 7 is a rear view showing the general arrangement of the drier.

Referring first to Figures 1 and 2 of the drawings the clothes drier 10 illustrated therein includes an outer shell or cabinet 11 in which is mounted a rotating drum 12 which is arranged to receive clothes or other articles to be dried.

2

The drum 12 is mounted for rotation about a horizontal axis and is arranged to be driven by a motor 13 through a belt drive 14.

The cabinet 11 of the drier 10 is provided with an opening in the front wall thereof opposite the drum 12 as defined by a circular flange 15. The drum 12 has a peripheral wall 16, a rear wall 17 and a forward wall 18. The forward wall 18 has a central opening therein which is defined by a forwardly turned lip or flange 19.

The forwardly turned lip or flange 19 of the drum 12 is disposed radially outwardly of the innermost end flange portion 20 of the flange 15. The flange or lip 19 carries a felt ring 21 which is secured to the flange 19 in any suitable manner. This felt ring 21 extends beyond the flange 19 into engagement with the shoulder 22 on the flange 15. It will thus be understood that while the drum 12 rotates with respect to the cabinet 11, a reasonably good air seal is provided between the opening in the front wall 18 of the drum 12 and the forward wall of the cabinet 11.

In order to have access to the drum 12 so as to be able to introduce clothes or other articles into the drum through the opening defined by the lip or flange 15, a door 23 is provided for the cabinet 11. This door 23 is arranged to lie substantially flush with the front wall or panel 24 of the cabinet 11 and accordingly the door 23 is arranged to be nested within the flange portion 15 of the cabinet 11 so as to be seated substantially against the shoulder 22. The door 23 is provided with a grill 24 through which air may circulate. Air intake holes 25 are provided in the back of the housing or casing 11, as is clearly shown in Figure 7.

As may be seen best in Figures 1 and 5 of the drawings, the drum 12 is mounted on a pedestal 26 which is in the form of an upstanding tubular member 27 having a pair of diverging legs 28. The diverging legs 28 are made up of a single channel-shaped bracket which is wrapped around the tubular member 27 and welded or otherwise suitably secured thereto. It will be observed that the legs 28 which form this bracket extend well beneath the rotating drum 12 and thus supply a satisfactory rigid base for the rotating assembly.

A bearing support sleeve 29 is seated on the top of the tubular member 27, the latter being cut away so it fits snugly around a portion of the sleeve 29 (see Fig. 1). The sleeve 29 may be welded or otherwise suitably secured to the top of the tubular member 27.

Within the tubular sleeve 29 are disposed two

bearing sleeves 30 and 31 which may, by way of example, be porous metal lubricant-impregnated bearing sleeves. These bearing sleeves 30 and 31 are disposed at opposite ends of the stationary sleeve 29. In order to provide additional lubricant a felt or other packing ring is carried in the sleeve 29 between the two bearings 30 and 31.

The rotating drum 12 is provided with a frame or spider in the form of three radially extending supporting arms 33, 34 and 35. These arms 33, 34 and 35 are secured to a hub 36 which in turn is mounted on and secured to a shaft 37. The shaft 37 extends through the bearings 30 and 31 and thus supports the drum 12 on the pedestal 26. The rear end of the shaft 37 is of slightly reduced diameter and has secured on its outer extremity a large pulley 38 which is the main drive pulley for the drum 12, as will hereinafter be explained.

Between the end of the sleeve 29 and the large drive pulley 38 a fan hub 39 is rotatably mounted. The fan hub 39 has its rearward end provided with a V-groove 40 for receiving the V-belt 14 from the motor 13. The fan hub 39 is also provided with a bearing 41 which may, by way of example, be a porous metal lubricant-impregnated bearing sleeve. An oil-impregnated felt ring 42 is mounted in a suitable recess between the bearing sleeve 41 and the hub 39 at an intermediate portion thereon.

A blower 43 having a plurality of blades 44 held together by end rings 45 and 46 is mounted on the hub 39. As illustrated, this blower 43 is of the type which sucks air in axially and throws it out radially within a scroll casing 47.

Before the air heating and circulating system of the present invention is described, attention is directed to the fact that the blower 43 is driven at a much higher speed than the speed of rotation of the drum 12. This is accomplished by causing the belt drive 14 which extends around the motor drive pulley 48 and the V-groove 40 of the hub 39 to also pass around a large idler pulley 49 which is mounted for free rotation on a sub shaft 50. The idler pulley 49 has associated therewith a pulley 51 of much smaller diameter which lies in the plane of the large drum pulley 38. A second V-belt 52 extends around the small pulley 51 and the large drive pulley 38. It will thus be understood that a substantial speed reduction is obtained between the motor drive pulley 48 and the large drum pulley 38 which is driven thereby. The sub shaft 50 may be suitably biased by a helical spring 53 to tension the main drive belt 14.

One of the principal features of novelty of the present invention lies in the manner in which the air is heated and circulated in the drier. Since the manner in which the air passes through the device is somewhat peculiar it is necessary, in the ensuing description, to carefully bear in mind all of the various figures of the drawings.

As previously indicated, the air inlet openings for the general housing 11 are the openings 25 in the rear wall of the housing 11. These holes 25 do not directly connect with any ducts. The blower 43, as previously pointed out, is mounted within a housing or scroll casing 47 which is supported at its upper end on the bearing supporting sleeve 29 through a bracket 54 and a bracket cross-arm 55. The blower housing 47 is made up of two sheet metal parts 56 and 57 which are bolted or otherwise suitably secured together after the blower 43 has been mounted therein. The housing forms an air intake duct 58 which

extends diagonally downwardly from the blower 43. The enlarged upper portion of the housing 47 has its inner peripheral wall (as considered with respect to the blower 43), spirally shaped about the axis of rotation of the blower. This means that the inner peripheral wall of the housing 47 is quite close to the blades 44 of the blower 43 at one point, and then gradually becomes farther and farther away from the blower blades. This, of course, is standard scroll casing practice for any blower of the type herein illustrated.

The plate member 47, which forms the rear housing member of the housing 47, has a circular opening therein which is defined by an inturned flange 59. The flange 59 is located radially inwardly of the blades 44 and is concentric with the axis of rotation of the blower 43. This opening defined by the edge 59 is therefore the air intake opening to the blower 44. Upon rotation of the blower it will be apparent that air will be forced downwardly through the air duct 58, where it is passed into the gas heating unit which will now be described.

The gas heating unit of the drier 10 includes a double walled housing 60 which is mounted on the base 61 of the drier 10 and extends from a region in proximity to the front wall 24 of the drier 10 to a region in proximity to the rear wall 62. The heating unit 60 includes an outer shell 63 and an inner shell 64. The two shells 63 and 64 are welded or otherwise suitably secured to a forward wall 65. The inner shell 64 is provided with a rear wall 66 which is welded or otherwise suitably secured thereto, and seals off the rear end of the inner shell 64.

An opening 67 is provided in the forward wall 65 and a gas pipe 68 also extends through the forward wall 65. The gas pipe 68 is provided with a series of burner openings 69 through which the gas escapes. A stack 70 extends from the inner shell 64 out through the top of the housing 11 and conveys away the products of combustion of the burning gas supplied from the gas pipe 68. The gas pipe 68 has a suitable gas control valve therein which is operated by a handle extending through the lower front wall of the housing 11.

The space between the inner shell 64 and the outer shell 63 provides a passageway through which the air is forced by the blower 43 on its way to the drum 12. The outer shell 63 has an end wall 72 which is welded or otherwise suitably secured thereto. Although the stack 70 passes through the space between the inner shell 64 and the outer shell 63, it will be observed that there is no air connection between the two. Now this chamber between the inner shell 64 and the outer shell 63 is divided up by partitions in such a manner that the air has a long circuitous passageway over the outer surface of the inner shell 64. By providing such a long and circuitous passageway adequate time is provided for raising the temperature of the air to the desired temperature for drying the clothes or other articles in the rotating drum 12. One partition 65 is inserted between the inner shell 64 and the outer shell 63 in the form of a plate 73 which extends from the stack wall 70 to a point 74 spaced somewhat back from the forward wall 65. A second partition 75 is provided which lies substantially in a plane at right angles to the partition 73 and in proximity to the lower end of the duct 58. This partition 75 extends upwardly from the bottom wall of the outer shell 63 between the side walls of the inner and outer shells 64 and 63 to a point where it is seated

70
75

tightly against the stack 70 (see particularly Figs. 2 and 3).

The blower housing 47 with its lower duct portion 58 is directly connected to the outer shell 63 by means of a collar 76, a hole 77 being cut in the outer shell 63 for direct connection with the duct 58. It will be noted that this hole 77 is located rearwardly of the partition 75. A second hole or opening 78 is cut in the outer shell 63 forwardly of the partition 75 and on the same side. This opening 78 opens into an air outlet duct 79 which is formed of two casing halves 80 and 81. The housing formed by the casing halves 80 and 81, in addition to the lower duct portion 79, includes an annular duct portion 82 which is concentrically located around the drum shaft 37, it being noted, of course, that the duct 79 merges into the annular duct 82. The front casing half 80 of this annular duct 82 is provided with a plurality of openings 83 which are located within the axially extending flange 84 which defines the large opening in the rear of the drum 12.

From the above description it will be apparent that air which is taken in by the blower 43 is forced down through the duct 58 into the outer shell 63 of the gas heating unit, through the opening 77. It then passes down over the heated inner shell surface 64 on the side and top which lies to one side of the partition 73. It then passes across to the other half of the gas heating unit through the opening which is provided between the forward end 74 of the partition 73 and the forward wall 65 of the gas housing unit. It then passes back over the other half of the inner shell 64 where it is further heated and then out through the opening 78 into the outlet duct 79. From here the heated air passes up into the annular duct 82 and then out through the openings 83 into the rotating drum 12. In passing through the rotating drum 12 it dries the clothes or other articles therein and finally escapes through the grill 24 of the door 23.

The above described structure provides an extremely compact and inexpensive clothes drier, and yet, at the same time, provides an arrangement in which the air can be quickly and efficiently heated to a relatively high point before it is passed through the clothes drum where the clothes or other articles are being tumbled.

While I have shown a particular embodiment of my invention and described a particular method of operation, it will, of course, be understood that I do not wish to be limited thereto, since many modifications may be made, and I, therefore, contemplate by the appended claims, to cover all such modifications as fall within the true spirit and scope of my invention.

I claim as my invention:

1. In a clothes drier of the type wherein a clothes-receiving drum having end members through which air may be circulated is disposed within the casing of the drier for rotation about a substantially horizontal axis, an air heating device comprising a combustion chamber having a burner therein, a second chamber surrounding at least a portion of said combustion chamber, baffle means within said second chamber to provide a circuitous air passageway therethrough over said combustion chamber, and means for circulating air through said second chamber and then through said drum.

2. In a clothes drier of the type wherein a clothes-receiving drum having end members through which air may be circulated is disposed within the casing of the drier for rotation about

a substantially horizontal axis, an air heating device comprising a combustion chamber having a gas burner therein, a second chamber surrounding at least a portion of said combustion chamber, baffle means within said second chamber to provide a circuitous passageway for air circulating therethrough over said combustion chamber, an air inlet duct communicating with said second chamber at one end of said circuitous passageway, an air feeder duct leading from said second chamber from the opposite end of said circuitous passageway to one end of said drum, and a blower in said inlet duct.

3. In a clothes drier of the type wherein a clothes-receiving drum having end members through which air may be circulated is disposed within the casing of the drier for rotation about a substantially horizontal axis, an air heating device comprising a combustion chamber having a gas burner therein, a second chamber surrounding at least a portion of said combustion chamber, baffle means within said combustion chamber to provide a circuitous path over said combustion chamber around which air must pass when it is circulated through said second chamber, an air inlet duct communicating with said second chamber at one end of said circuitous path, the open end of said duct being located to the rear of said opening in said rear wall of said drum, an air feeder duct leading from said second chamber at the opposite end of said circuitous passageway to a point directly opposite said opening in said rear wall of said drum, and opening toward said opening in said wall, and a blower at the inlet end of said inlet duct.

4. An article drier comprising a support, a drum rotatably mounted on said support, said drum having ends with openings therein through which air may pass, a heating device displaced laterally from the axis of said drum having an air intake duct leading thereto and a discharge duct leading therefrom and terminating opposite an opening in an end of said drum, the intake end of said inlet duct and the discharge end of said outlet duct both being disposed coaxially of said drum, and an air moving element disposed to move air through said ducts and said heating device.

5. An article drier comprising a support, a drum rotatably mounted on said support, said drum having ends with coaxial openings therein, a heating device displaced laterally from the axis of said drum having an air intake duct leading thereto and an air discharge duct leading therefrom, the intake end of said inlet duct being disposed coaxially of said drum and facing away from said drum, the discharge end of said outlet duct being disposed coaxially of said drum between said intake end of said inlet duct and said drum and facing said drum, and an air moving element disposed in said duct and heating device system for drawing air in through said inlet duct and discharging it from said outlet duct through said drum.

6. An article drier comprising a support, a drum rotatably mounted on said support, said drum having ends through which air may circulate, a combustion chamber having a burner therein, an air heating chamber including an inlet port disposed coaxially of said drum, a heat transfer section immediately adjacent said combustion chamber and a discharge port disposed coaxially of said drum immediately adjacent an open end thereof, and means for drawing air in through said coaxial inlet port, through said air heating

chamber and then discharging it from said discharge port into said drum.

7. In a clothes drier of the type wherein a clothes-receiving drum having end members through which air may be circulated is disposed within the casing of the drier for rotation about a substantially horizontal axis, an air heating device comprising a combustion chamber extending lengthwise in the casing for substantially the entire length thereof, a closed heating chamber adjacent said combustion chamber having communication with one end of the drum, and a blower mounted in said casing for drawing air thereinto and directing it through said heating chamber, said heating chamber being divided lengthwise into two connected passageways so that air is forced to travel down one passageway for the entire length of the combustion chamber and return through the other passageway and then into said rotating drum.

8. In a clothes drier of the type wherein a clothes-receiving drum having end members through which air may be circulated is disposed within the casing of the drier for rotation about a substantially horizontal axis, an air heating device comprising a combustion chamber extend-

ing longitudinally in the casing adjacent the drum, a U-shaped air heating chamber surrounding said combustion chamber and divided into two connected passageways by a baffle plate which extends longitudinally for a portion of the length of the heating chamber, a discharge passage from said heating chamber in communication with one end of said drum, an inlet passage connected to said heating chamber and a blower connected in said inlet passage.
